UNITED STATES PATENT OFFICE.

ADOLF SCHMIDT, OF CHICAGO, ILLINOIS, ASSIGNEE TO COLUMBIAN THREE COLOR CO.,
OF CHICAGO, ILLINOIS, A CORPORATION OF ILLINOIS.

ORNAMENTAL FLOCKED DESIGN.

1,168,747.

Specification of Letters Patent. Patented Jan. 18, 1916.

Application filed May 11, 1914. Serial No. 837,798.

To all whom it may concern:

Be it known that I, ADOLF SCHMIDT, a citizen of the United States, residing at Chicago, in the county of Cook, and State of Illinois, have invented a new and useful Improvement in Ornamental Flocked Designs, of which the following is a specification.

My invention relates to an improvement 10 in the art of design-printing, and more particularly in the art of printing designs in one or more colors, by impressing upon the sheet-surface to be printed the design-carrying surface of a "printing-plate".

15 The primary object of my invention is to provide such plate-printed surfaces in close imitation, especially as to fluffy texture and color, of a textile fabric, thereby to enhance the attractiveness of such designs for advertising purposes, as by salesmen's cards, in displaying rugs, carpets, cloth, clothing and the like, and for wall-paper and the like.

20 In the accompanying drawing, Figure 1 is a plan view of a broken section of a print 25 showing a rug-design and involving my invention, and Fig. 2 is an enlarged section on line 2, Fig. 1, showing the parts greatly exaggerated.

25 To reproduce a variegated article by my invention, the design is produced with flock 30 of different colors cemented to the surface employed through the medium of printing-plates carrying different portions of the design each coated with a size 4 of varnish or 35 other suitable cementitious substance. These plates, after thus coating each, are impressed in proper succession, preferably in the ordinary manner of plate-printing by a printing press, on the surface of a sheet 3, of 40 paper or other desired material, thereby transferring to the surface of the sheet the respective portion of the design in size. After each application of a printing-plate, flock 5, of wool, silk, cotton, or other suitable fibers, and of desired color, is dusted or 45 blown on the sheet-surface to become cemented thereto by the size, and is thereupon dried before applying the next printing-plate. Any superfluous flock or portion 50 thereof which may be applied to spaces on the transferred design or configuration that

are left uncoated with the cementitious size will not adhere to the surface and may be dusted off.

To reproduce the rug represented at 6 on Fig. 1, or any analogous variegated article, each portion of the design for a different color to be reproduced by the flock is provided on a separate printing-plate. Then the plate carrying the part of the design to be first applied, as for reproducing the background, has the design thereon coated with the size and transferred, in the manner described, to the sheet, whereupon flock of the desired color, as red, is blown or dusted thereon, and the superfluous flock is removed. When this is dried, the plate carrying the portion of the design next to be applied is coated in the same way and similarly transferred to the sheet, in proper registration with the portion of the flock-covered design previously provided thereon; and then more flock of desired color, as yellow, is dusted or blown on the sheet to adhere to the size-covered parts of the design-portion thereon, and that part of this flock which does not adhere is dusted off. In the same way, flock of different colors, as black, blue, and the like, may be applied in succession and in proper registration, to complete the reproduction of a variegated rug, carpet, or other textile article, care being taken to cause each flock-portion of the design thus applied to extend edgewise to the precedingly applied flock-portion.

Prints of designs of textiles thus produced on sheets of ordinary printing paper, card board and the like, present a very close resemblance to the fuzzy or flocculent textile surface as well as to its coloring, thereby rendering the prints peculiarly desirable for exhibition in advertising-display matter; and such prints provide very rich effects in wall-paper.

I do not claim in the present application the process herein described, but reserve the right to claim the same in a separate future application for Letters Patent.

What I claim as new and desire to secure by Letters Patent is—
As a new article of manufacture, a sheet provided on one surface with a solid varie-

gated flock design having a fuzzy or textile-like appearance, and composed of registering applications of cementitious size each forming a portion of the design to be produced, and flock of varying colors applied to said applications of cementitious size, each flock-portion of the design registering

with and extending edge-wise to the adjacent differently colored flock-portion thereof.

ADOLF SCHMIDT.
